SCREEN CLEARER FOR GYRATORY SIFTERS

Howard H. Moyer, Lockport, N. Y., assignor to
Richmond Manufacturing Company, Lockport,
N. Y., a corporation of New York

Application December 6, 1945, Serial No. 633,204

5 Claims. (Cl. 209—381)

1

This invention relates to a screen for gyrating sifters, screens or bolting equipment and more particularly to such a screen which works in conjunction with loosely supported screen cleaners, such screen cleaners bouncing and moving erratically below the surface of the screening cloth and serving to keep the meshes of the sifting, screening or bolting silks, wires or other screening elements from clogging with the material being separated or graded. The invention is particularly applicable to high speed gyrating sifters, that is, sifters describing from one and one-half to three inch circles at a speed of from 250 to 300 R. P. M. as compared with earlier low speed gyrating sifters operating at approximately 180 R. P. M. and describing a larger circle in the order of four inches in diameter. The high speed sifter has a remarkable bolting or sifting action but with certain stocks, such as sulfur, has not proved to be advantageous due to the lack of an adequate cleaner medium. The present invention is directed to the efficient cleaning of the screening cloth to achieve the advantage of high speed gyratory sifting with materials which tend to blind the cloth, although the invention is not, of course, limited in its use to a high speed sifter nor to any type of stock and in particular can be used advantageously in bolting such materials as wheat flour in which use the capacity of the screen is greatly increased.

This application is a companion to the copending application for patent of Percy Pickard, Serial No. 774,368, filed September 16, 1947, now Patent No. 2,455,383, December 7, 1948, and to my application Serial No. 633,203, filed December 6, 1945, both for screen for gyrating shake sifters.

Screens for gyrating sifters or bolting equipment are usually arranged in a stack and each screen of the stack is usually in the form of a rectangular wooden frame which may be divided by central wooden cross pieces into rectangular sections and over which is stretched the sifting, bolting or screening cloth of silk, wire cloth or the like which effects the separation of the material being graded. Below this sifting, screening or bolting cloth is usually arranged a cleaner carrier usually in the form of a grate of coarsely woven wires and on which the screen cleaners are loosely supported. These screen cleaners bounce around erratically to strike the underside of the sifting, screening or bolting cloth to keep the mesh thereof from blinding. Below the cleaner carrier is frequently arranged a sheet metal plate or imperforate surface which serves to direct the screened material laterally into the

2

proper channels or ways provided at the sides of the screen frames. However, the use of a sheet metal plate of this character is optional, the spaces between the screens in the stack often being left open so that the product from one screen drops onto the next lower screen and is not carried out on such interposed metal plate.

It has been found that with materials which are difficult to sift, such as sulfur, the capacity of the sifter is greatly increased if the activity of the screen cleaners is increased and in particular if the activity of the screen cleaners is extended uniformly to the corners and extremities of the screening cloth in opposition to the normal tendency of the screen cleaners to concentrate their action in the center of the screening cloth which tendency not only permits excessive blinding of the corners and extremities of the screening cloth but also results in excessive wear on the center of the screening cloth. It has also been found that the capacity of the sifter is greatly increased if a continued jarring of the screen is effected, such jarring being effective both with bolting silks and unstretchable wire cloth to prevent the screen from blinding.

It is accordingly the principal object of the present invention to provide a screen for a gyrating shake sifter in which the mesh of the screening cloth is prevented from blinding thereby to permit of sifting such materials as sulfur and to increase the overall efficiency and capacity of the screen with normal materials.

Another object of the invention is to provide such a screen in which the activity of each screen cleaner is increased and in which the tendency of each screen cleaner to remain at the center of the compartment in which it is normally confined is restrained and in which, in particular, each screen cleaner is kept in rapid action and is thrown to all parts of the screen to act uniformly on all parts of the screening cloth thereby to increase the overall efficiency and capacity of the screening cloth as well as to secure uniform wear thereof.

Another object of the invention is to provide, in such a screen, means for jarring the screening cloth which is effective, both with fiber and metal screening cloths, to materially increase the screening capacity of the screening cloth and to permit of sifting materials which are difficult to sift.

Another most important object of the invention is to increase the effective screening area for a screen of a given size, this being effected by the elimination of cross bars normally employed in

a screen frame and which very materially reduce the effective face area of the screening cloth.

It is a further object to provide a screen in which this jarring action is derived from the erratic movement of the screen cleaners.

Another object is to provide such a screen in which there is minimum wear, particularly of the screening cloth.

Another object is to provide such a screen in which the permitted movement of each screen cleaner is reduced to secure increased activity of the screen cleaners.

Another important object is to support the screening cloth in such manner that it is prevented from sagging when it becomes stretched or when a heavy load is placed upon the same and at the same time does not cut or wear the screening cloth.

Another object is to provide such a screen in which the means for reducing the permitted movement of each screen cleaner is a part of the structure for so supporting and jarring the screening cloth and thereby is acted upon by all of the screen cleaners for a screen frame.

Another object is to provide such a structure for supporting and jarring the screen cloth which can be made to act upon the screening cloth at a plurality of places.

Another object is to provide such a screen in which a lighter grade of woven wire can be used for the cleaner carrier and in particular in which low cost standard galvanized hardware mesh can be employed.

Another object is to provide such a screen which is simple and inexpensive in construction and which will stand up under conditions of severe and constant use without getting out of order or requiring repairs.

Other objects and advantages will appear from the following description and drawings, in which:

Fig. 1 is a top plan view of the inner frame of a screen embodying the present invention and showing a part of the screening cloth broken away.

Fig. 2 is a vertical section, taken on line 2—2, Fig. 1.

Fig. 3 is an enlarged, horizontal, fragmentary view taken on line 3—3, Fig. 2.

Fig. 4 is an enlarged, vertical, fragmentary section taken on line 4—4, Fig. 1.

Fig. 5 is a view similar to Fig. 1 of a modified form of the invention and showing the screening cloth removed.

Fig. 6 is a vertical section taken on line 6—6, Fig. 5.

In Figs. 1—4 is illustrated the inner frame of one unit or screen for sifting, bolting, separating, screening or grading material into different sizes, such screens or units being usually piled one on top of the other to form a stack and the stack of such screens or units being arranged in a gyrating machine so that a gyrating action is imparted to the stack, usually in a generally horizontal direction.

Each of these screens includes an inner wooden frame 10 preferably of square or rectangular form having side bars 11 connected by end cross bars 12, the side bars 11 being shown as somewhat higher than the cross bars 12 and as having a strip 13 of felt applied thereto. At one end of the screen the ends of the side bars 11 are extended, as indicated at 14, to connect with an outer screen frame (not shown) and provide the usual "throughs" and "overs" passages which extend vertically through the stack of screen frames.

The area defined by the inner frame of the screen is divided by a central longitudinal wooden bar 15 which connects the central parts of the end cross bars 12 and the two areas provided by this central longitudinal wooden bar 15 are in turn divided by a pair of central cross bars 16 each connecting the central part of the central longitudinal bar 15 with the corresponding side bar 11. The upper faces of these central bars 15, 16 are preferably coplanar with the upper faces of the end cross bars and with steps 18 provided in the longitudinal bars 11, the screening cloth 20 being applied to these coplanar faces and being secured to the end cross bars 12 and the steps 18 of the longitudinal bars 11 in any suitable manner. This screening cloth 20 can be of fabric, such as bolting silk, or can be of woven metal wire screening.

A rectangular grid 21 of coarse woven metal wire is shown as applied to the underside of the inner frame of the screen, the edges of this grid being shown as recessed into the longitudinal cross bars 11, 12 and as engaging the under faces of the central bars 15, 16. This wire grid forms a cleaner carrier and can be secured to the inner frame in any suitable manner. In the practice of the invention standard hardware galvanized grade of square mesh woven wire can be employed, such grade being very low in cost as compared with the heavier grades now required. It will be seen that the screen frame bars 11 and 12; central bars 15 and 16; screening cloth 20 and cleaner carrier 21 provide enclosed rectangular compartments 22 which in the screen shown are four in number.

The screen cleaners 23 in each of these compartments 22 can be of any form but each is shown as being in the form of one or more rubber balls. However, as illustrated in the said Pickard application these cleaners can be merely strips of cotton belt or can be in the form of so-called figure 8 cleaners, each comprising a leather figure 8 body having bristles projecting upwardly from its extremities. The screen cleaners can also be in the form of cylindrical rubber blocks.

The principal feature of the present invention resides in the provision of a structure or grid which divides the compartments into subcompartments for the screen cleaners and carrying section pads which support and engage the screening cloth 20 near the center of each of the compartments 22, the screen cleaners continuously striking and bodily displacing this structure or grid and having their activity greatly increased and agitating the pads to continuously jar the screening cloth through motion derived from the cleaners. By providing such a supporting structure which subdivides each compartment 22 into subcompartments the travel of each cleaner is restricted thereby to increase the effectiveness of each cleaner both in its direct action against the screening cloth and also in jarring the supporting structure and the pads carried thereby. Further, the supporting structure is so constructed that it does not blind or block off any part of the screening cloth 20 thereby to render the full area of the cloth over the compartments 22 available for screening purposes.

In the form of the invention shown in Figs. 1—4, this supporting structure or grid, indicated generally at 25, for the pads is in the form of a pair of sheet metal strips 26 and 28 arranged to form a rectangular cross with the ends of 75 the arms thereof secured to the four wood bars

defining each compartment 22 so as to subdivide each of these compartments 22 into four subcompartments 22a. Each of these strips is in the form of a relatively thin laterally flexible strip arranged vertically on edge within the compartment with its upper horizontal thin edge in closely spaced relation to the screening cloth. Each cross strip 28 is centrally notched on its underside, as indicated at 29, and the cross strip 26 is centrally notched on its under side, as indicated at 30, these notched portions being fitted together as shown in Fig. 4. The opposite extremities of the strips 26 and 28 are bent to provide perpendicular ears 31, these ears being screwed or otherwise secured to the opposing faces of the wooden frame bars 11, 12, 15 and 16 in each compartment 22. These cruciform supporting strips 26, 28 are preferably secured as to contact the cleaner carrier grid 21 but do not extend the full height of the compartments 22, thereby to be spaced a substantial distance from the screening cloth 20 to avoid any blocking off or blinding of the screening cloth and to avoid cutting or wearing the clothing should it become loose enough to sag.

Each screening cloth engaging pad is mounted on the central cross part of the cruciform supporting structure 26, 28. On top of this central cross part of this cruciform supporting structure is secured, as by solder 32, a sheet metal disk-like plate or seat 33. A pad 35 of nonabrasive material is secured to the upper face of this plate or seat and engages the underside of the screening cloth 20 or a patch 36 secured to the underside of the screening cloth at this point and holds the screening cloth in closely spaced relation to the strips 26, 28. The pad 35 can be made of many nonabrasive materials, such as mohair plush, but is shown as being made of rubber and vulcanized or glued to the disk 33. The strips 26, 28 are of such thinness as to be bodily displaced by the impacts of the screen cleaners in the normal operation of the sifter whereby the striking of the strips by the screen cleaners bodily displaces the strips and pads to effect jarring of the screen cloth.

In the operation of the form of the invention shown in Figs. 1-4, a plurality of screen frames, each with at least one ball 23 or other screen cleaner in each subcompartment 22a, are stacked and mounted in a gyrating machine. The material to be sifted is fed to the screening clothing of the several gyrating screen frames which separate the material passing therethrough. This separated material tends to remain in or blind the screening cloth thereby to reduce the capacity of the screening cloth with normal materials, such as wheat flour, and to rapidly render the screening cloth completely inoperative with other materials, such as sulfur.

The direct action of the screen cleaners 23 tends to relieve this blinding condition, these screen cleaners bouncing erratically around in the subcompartments 22a and continuously striking the underside of the screening cloth 20 to free the interstices thereof. The frequency of this activity of the screen cleaners 23 is increased by the resilience of the cruciform supporting structure 26, 28 and the smallness of the subcompartments 22a as compared with the compartments 22. The screen cleaners 23 continuously strike the sides of the cruciform strips 26, 28 secured in each compartment 22 and dividing each of these compartments into rectangular subcompartments. This bodily displaces and jars

the entire structure formed by these cross strips and in particular the supports provided by the central crossed parts of these strips and the disks 33 and nonabrasive pads 35 mounted thereon.

Each of these nonabrasive pads 35 is in engagement with the underside of the screening cloth 20, or a wear patch 36 sewed thereon, at the center of each compartment 22 and hence this jarring of these pads 35 serves to jar the screening cloth at the center of each of the compartments 22. This jarring of the screening cloth has been found to be remarkably effective in combination with the increased frequency of action of the cleaners, in reducing blinding of the screening cloth and thereby in increasing the overall efficiency and capacity of the screens. Thus with normal materials, such as wheat flour, a very marked increase in capacity results from the use of the posts supported by the cruciform support as described, and materials, such as sulfur, which had heretofore been impossible or extremely difficult to sift with a gyratory sifter of this character, or other types of sifters, are readily screened. It will also be noted that with the supporting structures shown the activity of the screen cleaners is distributed uniformly over the screening cloth both to increase their overall cleaning efficiency and to reduce localized wear on this screening cloth. Further these structures do not decrease in any way the effective area of the screening cloth.

In the form of the invention shown in Figs. 5 and 6, the outer longitudinal and cross bars 11 and 12 are the same as with the form of the invention shown in Figs. 1-4 and the screening cloth and cleaner carrier are secured thereto in the same manner and the same reference numerals have accordingly been applied.

However, the central wooden bars 15, 16 shown in Figs. 1-4 are eliminated, and the single compartment provided by the longitudinal and cross bars 11, 12, cleaner carrier 21 and screening cloth 20 is divided by a unitary metal support indicated generally at 40 into a plurality of rectangular subcompartments 22c. This support is shown as made in the form of a die casting having a plurality of spaced longitudinal bars or strips 41 crossed at right angles by a plurality of spaced cross bars or strips 42, the opposite extremities 50 of each of these longitudinal and cross bars 41, 42 being provided with laterally extending ears 43 which are secured by screws 44 to the opposing inner faces of the wooden frame bars 11 and 12. However, this support can be made of the jointed metal strips as with the form of the invention shown in Figs. 1-4. At each cross between the bars or strips 41 and 42 the structure is provided with a disk-like plate or seat 45 which faces upwardly. On this disk-like plate or seat a nonabrasive pad 46 of rubber, mohair or the like is vulcanized, glued or otherwise secured, these pads engaging and supporting the underside of the screening cloth, or patches thereon, as with the form of the invention shown in Figs. 1-4.

It will be seen that the form of the invention shown in Figs. 5 and 6 operates in the same manner as the form of the invention shown in Figs. 1-4. Thus at least one of the screen cleaners 23 is placed in each of the subcompartments 22c. In addition to the increased frequency of movement and more uniform action of these screen cleaners in keeping the screening cloth from blinding, by so confining the screen cleaners, as the screen cleaners 23 strike the crossed bars or strips 41, 42 of the structure 40 they bodily dis-

place and jar the structure and this jarring movement is transmitted through the rubber pads 46 to the screening cloth so as to effect a jarring thereof, this being effective in combination with the accelerated activity of the screen cleaners, as previously stated, to prevent blinding with difficult materials, such as sulfur, and to increase the efficiency and capacity of the screen with normal materials.

It will further be noted that the form of the invention shown in Figs. 5 and 6 provides substantially greater screening area than the form of the invention shown in Figs. 1-4 and also provides substantially greater screening area than the usual Brantingham type of sieve shown. Thus in Figs. 1-4, and in the usual Brantingham type of sieve, a substantial area of the screening cloth is blocked off by the wooden central bars 15, 16. In Figs. 5 and 6 these central bars are eliminated and as the strips or bars 41, 42 of the structure 40 are spaced a substantial distance from the screen cloth, the full area of this screen cloth, as defined by the frame bars 11 and 12, is useful.

From the foregoing it will be seen that the present invention provides a simple and inexpensive form of screen which will handle materials not heretofore capable of commercial separation on a gyratory sifter and which has increased efficiency and capacity for normal materials as compared with screens of similar size now in general use.

I claim as my invention:

1. A screen for gyratory sifters gyrated in a horizontal plane to describe circles, comprising, in combination, a rectangular screen frame having opposed generally parallel side walls, a generally horizontal screening cloth arranged on said frame, a generally horizontal foraminous cleaner carrier arranged on said frame below said screening cloth and forming with said frame and said screening cloth an enclosed compartment, a relatively thin laterally flexible strip arranged vertically on edge within said compartment with its upper longitudinal thin edge adjacent said screening cloth and in spaced relation thereto, means connecting the opposite ends of said strip with two of said opposite generally parallel side walls of said frame and in spaced relation with the other generally parallel side walls of said frame to provide two subcompartments in said compartment, a freely movable screen cleaner in each subcompartment and engageable with said screening cloth, said strip being of such thinness as to be bodily displaced by the impacts of said screen cleaners in the normal operation of the sifter, and a flat pad mounted on said strip in spaced relation to said frame and engaging and supporting said screening cloth in said spaced relation to said strip, the striking of said strip by said screen cleaners bodily displacing said strip and said pad thereby to effect jarring of said screening cloth.

2. A screen for gyratory sifters gyrated in a horizontal plane to describe circles, comprising, in combination a rectangular screen frame having opposed generally parallel side walls, a generally horizontal screening cloth arranged on said frame, a generally horizontal foraminous cleaner carrier arranged on said frame below said screening cloth and forming with said frame and said screening cloth an enclosed compartment, a pair of crossed relatively thin laterally flexible strips each arranged vertically on edge within said compartment with its upper longitudinal thin

edge adjacent said screening cloth and in spaced relation thereto, means connecting the opposite ends of said strips with the corresponding opposite generally parallel side walls of said frame to provide at least four subcompartments in said compartment, a freely movable screen cleaner in each subcompartment and engageable with said screening cloth, said strips being of such thinness as to be bodily displaced by the impacts of said screen cleaners in the normal operation of the sifter, and a flat pad mounted on at least one of said strips in spaced relation to said frame and engaging and supporting said screening cloth in said spaced relation to said strips, the striking of said strips by said screen cleaners bodily displacing said strips and said pad thereby to effect jarring of said screening cloth.

3. A screen for gyratory sifters gyrated in a horizontal plane to describe circles, comprising, in combination, a rectangular screen frame having opposed generally parallel side walls, a generally horizontal screening cloth arranged on said frame, a generally horizontal foraminous cleaner carrier arranged on said frame below said screening cloth and forming with said frame and said screening cloth an enclosed compartment, a pair of crossed relatively thin laterally flexible strips each arranged vertically on edge within said compartment with its upper longitudinal thin edge adjacent said screening cloth and in spaced relation thereto, means connecting the opposite ends of said strips with the corresponding opposite generally parallel side walls of said frame to provide at least four subcompartments in said compartment, a freely movable screen cleaner in each subcompartment and engageable with said screening cloth, said strips being of such thinness as to be bodily displaced by the impacts of said screen cleaners in the normal operation of the sifter, and a flat pad mounted on the crossed part of said strips in spaced relation to said frame and engaging and supporting said screening cloth in said spaced relation to said strips, the striking of said strips by said screen cleaners bodily displacing said strips and said pad thereby to effect jarring of said screening cloth.

4. A screen for gyratory sifters gyrated in a horizontal plane to describe circles, comprising, in combination, a rectangular screen frame having opposed generally parallel side walls, a generally horizontal screening cloth arranged on said frame, a generally horizontal foraminous cleaner carrier arranged on said frame below said screening cloth and forming with said frame and said screening cloth an enclosed compartment, at least four crossed relatively thin flexible strips each arranged vertically on edge within said compartment with its upper longitudinal thin edge adjacent said screening cloth and in spaced relation thereto, means connecting the opposite ends of said strips with the corresponding opposite generally parallel side walls of said frame to provide at least eight subcompartments in said compartment, a freely movable screen cleaner in each subcompartment and engageable with said screening cloth, said strips being of such thinness as to be bodily displaced by the impacts of said screen cleaners in the normal operation of the sifter, and a flat pad mounted on each of said strips in spaced relation to said frame and engaging and supporting said screening cloth in said spaced relation to said strips, the striking of said strips by said screen cleaners bodily displacing said strips and said pads thereby to effect jarring of said screening cloth.

5. A screen for gyratory sifters gyrated in a horizontal plane to describe circles, comprising, in combination, a rectangular screen frame having opposed generally parallel side walls, a generally horizontal screening cloth arranged on said frame, a generally horizontal foraminous cleaner carrier arranged on said frame below said screening cloth and forming with said frame and said screening cloth an enclosed compartment, a multicellular grid member arranged in said compartment and secured at its margins to said frame and dividing said compartment into a multiplicity of sub-compartments, the upper side of said grid member being arranged in closely spaced relation to said screening cloth and presenting a relatively small opposing face, a freely movable screen cleaner in each subcompartment and engageable with said screening cloth, the members constituting said grid being of such horizontal thinness as to be bodily displaced by the impacts of said screen cleaners in the normal operation of the sifter, and a multiplicity of spaced pads mounted on said grid and engaging and supporting said screening cloth in said closely spaced relation to said grid,

the striking of said grid by said screen cleaners bodily displacing said grid and said pads thereby to effect jarring of said screening cloth.

HOWARD H. MOYER.
